UNITED STATES PATENT OFFICE

ERNST HOFFMANN, OF SALZA, NEAR THE HARZ, GERMANY, ASSIGNOR TO SCHMIDT, KRANZ & CO. NORDHÄUSER MASCHINENFABRIK AKTIEN-GESELLSCHAFT, NORDHÄUSER NEAR THE HARZ, GERMANY

PROPELLION CONVEYER

Application filed December 14, 1927, Serial No. 239,847, and in Germany December 15, 1926.

My invention relates to improvements in propulsion conveyers and one of the objects of the improvements is to provide an improved conveyer of the type in which reciprocating movement is imparted to the trough, table, or other support by means of a pair of meshing elliptical gear wheels rotatably supported at one of the foci. Thereby the movement imparted to the support is first gradually accelerated during the forward stroke and rapidly retarded at the end of the forward stroke, so that during the first part of the forward movement of the support the material is carried along by friction and accelerated, while it overcomes friction by inertia during the rapid retardation of the support and continues its forward movement during the return stroke of the support.

The acceleration of the support during the first part of the forward stroke must not exceed a certain maximum in order to insure that the material will be carried along. If the friction of the material on the support is small the acceleration must be reduced. In my improved mechanism such retardation is obtained by connecting the driven elliptical gear wheel with the support at points more or less away from the major axis of the ellipse. Thereby the maximum velocity of the support during the forward stroke is reduced, and further the time taken for the forward stroke is made greater than the duration of the return stroke, both facts reducing the acceleration. With this new arrangement an unsymmetrical curve will be obtained in a diagram illustrating the varying velocity of the support during a complete cycle consisting of forward stroke and return stroke.

Preferably the driving mechanism is constructed so that the support can be connected at will to different parts of the driven elliptical gear wheel, so that the said mechanism can be adapted to different conditions, and more particularly to the quality of the material to be conveyed or the inclination of the support.

The point of connection between the support and the driven elliptical gear wheel can be changed to such a position that while the

driving mechanism is kept rotating in the same direction, the direction of the conveying movement will be reversed. In constructions heretofore proposed elastic means have been provided between the driven elliptical gear wheel and the support, in order to avoid the transmission of heavy jars from the support to the driving mechanism. If in constructions of this type too much material falls on the support it may happen that the load is such that the support is not reciprocated any more, but becomes stationary, the rotary movement of the driving mechanism being taken up by the elastic connection between the same and the support. In such cases it is necessary to remove the material from the support by hand. In my improved construction means are provided for limiting the elasticity of the connection provided between the elliptical gear wheel and the gutter. This will insure that even when the support is overloaded a certain amount of reciprocating movement will be imparted thereto, so that the material is gradually conveyed forwardly, and the overload is taken from the support.

When mounting the driving mechanism for example in mines it may happen that the standards by means of which the said mechanism is supported on the floor of the gallery transmit the pressure of the rock to the base frame of the mechanism, which is therefore pressed on the floor and deformed, so that the parts of the mechanism connecting the same to the base frame are broken. To overcome this drawback, in my improved conveyer the driving mechanism is secured to the base frame at two points only, and with its bottom part above the bottom part of the said base frame, so that the base frame can be deformed without exerting any stress on the driving mechanism.

For the purpose of explaining the invention an example embodying the same has been shown in the accompanying drawings in which the same reference characters have been used in all the views to indicate corresponding parts. In said drawings,

Fig. 1 is a somewhat diagrammatical elevation showing my improved conveyer,

Fig. 2 is a diagram of velocities of the support corresponding to the position of the crank pin on the major axis of the driven elliptical gear wheel, which position has been shown in Fig. 1 in dotted lines,

5 Figs. 3 and 4 are similar diagrams showing the velocities of my improved conveyer corresponding to two different positions of the crank pin,

10 Fig. 5 is an elevation showing the conveyer and its driving mechanism,

Fig. 6 is an elevation showing the casing enclosing the driving mechanism and illustrating the manner of mounting the same on 15 a base frame,

Fig. 7 is a plan view taken on the line 7—7 of Fig. 5 with the top portion of the apparatus removed,

20 Fig. 8 is a detail view showing the crank pin and the manner of mounting the same on the shaft carrying the driven elliptical gear wheel,

Fig. 9 is a side elevational view of Fig. 8, and

25 Fig. 10 is a detail view partly in section showing the connecting rod and its spring.

Referring at first to the diagrammatical view illustrated in Fig. 1, my improved propulsion conveyer comprises a support 1, elliptical gear wheels 2 and 3 having like pitch lines, a connecting rod 4 connecting the driven gear wheel 2 with the support 1, and driving means for the elliptical gear wheel 3 comprising a gear wheel 5 and a pinion 6 mounted on a shaft 12. The shafts 7 and 8 of the elliptical gear wheels pass through like foci of the ellipses. When the crank pin to which the connecting rod 4 is connected is located at a point on the major axis of the gear wheel 2, as is shown at 9 in Fig. 1 in dotted lines, the diagram of velocities of the support will be symmetrical for the forward and return strokes thereof, as is shown in Fig. 2. When rotating the gear wheel 2 from the position shown in Fig. 1 in the direction of the arrow α the movement is first slowly accelerated from the point a of the diagram, corresponding to the position of the crank pin shown at 9 in Fig. 1, to the point b , and the movement 45 is thereafter rapidly retarded to the point c , at which the gear wheel 2 has been turned through an angle of 180° . The support 1 then begins its return stroke, the velocity being first rapidly increased to the point d , whereupon it is gradually reduced to zero, when the crank pin is again in the position shown at 9 in Fig. 1, corresponding to the point a of the diagram.

During the first part of the forward stroke 60 of the support corresponding to the section $a—b$ of the diagram the velocity must be such that the material is carried along by the support. Thereafter the motion of the support is rapidly retarded according to the section $b—c$ of the diagram, so that the material,

by its inertia, will slide forward on said support. While the material is moving forwardly the support is retracted, its return movement, corresponding to the section $c—d$ of the diagram, being first rapidly accelerated and thereafter gradually retarded according to the section $d—a$. Thus the material is conveyed forwardly in the direction of the arrow y shown in Figs. 1 and 2.

70 If the friction of the material on the support is very small, it may happen that the support will not carry along the said material

when moving through the part of its forward stroke represented by the section $a—b$ of the diagram. Therefore the acceleration of the support on the part of the stroke corresponding to the section $a—b$ must be reduced. For this purpose the crank pin is disposed a suitable distance away from the major axis of the wheel 2, for instance at the point 9' shown in Fig. 1, so that the major axis 9—7 and the line 7—9' include a certain angle ω . By placing the crank pin at a point off the major axis of the wheel 2 the diagram of velocities is changed as is indicated by the examples 90 illustrated in Figs. 3 and 4, the diagram shown in Fig. 3 corresponding to an angle $\omega=22\frac{1}{2}^\circ$, and the diagram shown in Fig. 4 corresponding to an angle $\omega=45^\circ$ (see also Fig. 9).

95 As will appear from the said diagrams, the acceleration during the forward stroke of the support represented by the sections $a'—b'$ and $a''—b''$ is considerably reduced as compared to the acceleration shown in Fig. 2, first, because the maximum velocity represented by the points b' and b'' is smaller than the maximum velocity represented by the point b , and second, because the period of time t_1' or t_1'' of the forward stroke is considerably greater than the period of time t_2' or t_2'' of the return stroke. By comparing Figs. 2, 3 and 4 it will be found that the maximum velocity b' and b'' and the period of time t_1' and t_1'' differ in Fig. 4 to a greater degree than in Fig. 3 from the corresponding values b and t_1 respectively of Fig. 2. Thus the acceleration can be adapted to varying conditions, and more particularly to the friction of the material on the support and the position of the said support relatively to the horizontal, which support may be horizontal or inclined downwardly toward one end or the other. When the angle ω is 180° or over the resulting diagram of velocities will indicate that the direction of the feed is reversed without any reversal in the direction of the drive indicated by the arrow α . In this case also, the maximum speed and the time relation between the forward stroke and the return stroke can be varied by disposing the 100 crank pin at different angles ω .

110 For adapting the operating mechanism at any time to various conditions I prefer to construct the gear wheel 2, the crank shaft 7 and crank pin 9^a so that the said crank pin can 120

be set at different positions relatively to the major axis of the elliptical gear 2. Thus the same mechanism can be used in connection with supports disposed horizontally or inclined downwardly toward one end or the other, and the position of the crank pin can be altered at any time according to the character of the material to be conveyed, so as to set said pin in the most effective position.

10 Further, the crank pin can be secured to the gear wheel at an angle $\omega=180^\circ$ or over, for reversing the direction of the movement of the material without reversing the driving mechanism.

15 In Figs. 5, 6, and 7 I have illustrated the construction of the operating mechanism and the manner of mounting the same on a frame. As shown, the shafts 7 and 8 carrying the elliptical gear wheels 2 and 3 respectively and 20 the shaft 12 carrying the pinion 6 are mounted in a casing comprising a bottom part 10 and a removable top part 11. To the shaft 12 a pulley or other driving member 13 is keyed. To the outer end of the shaft 7 the crank pin 25 9^a is secured. In the construction shown the crank pin 9^a is made integral with or fixed to a disk 14 secured to a disk 15 made integral with or fixed to the shaft 7. As will appear more particularly from Figs. 8 and 9, the 30 disk 15 is provided with a large number of screw holes 16 disposed in an annular series the center of which is upon the axis of the shaft, so that the disk 14 may be secured to the disk 15 by means of screws 17 with the 35 crank pin 9^a in different positions relatively to the major axis of the center of said wheel 2 and on either side of the elliptical gear wheel.

40 The connecting rod 4 is associated with a spring 18 permitting such rod to yield lengthwise in case of an excessive load, in order to prevent the transmission of heavy jars to the driving mechanism. The arrangement of the said spring has been shown 45 in detail in Fig. 10. On the crank pin 9^a a bearing block 19 is mounted which is made integral with a stud 20 formed with a socket 21. By means of rods 22 a cross-head 23 is secured rigidly to the block 19, such cross-head 50 being formed with a bore 24. In bushings 25 and 26 of the socket 21 and the bore 24 respectively the connecting rod 4 is guided so as to be axially slid able therein. To one end of the said connecting rod is screwed or otherwise secured rigidly a disk 27, which is held in 55 position by means of a nut 28, and which is connected loosely with the stud 20 of the block 19 by means of bolts 29 provided with nuts 30, sufficient play being left between said 60 nuts and the stud 20 to permit a limited relative movement of the parts 27 and 19 to the extent indicated in Fig. 10 by the letter *g*. The coiled spring 18 interposed between 65 the cross-head 23 and the disk 27 tends to force the rod 4 inwardly and into the position

shown in Fig. 10. The power of the said spring is such that the mechanism is capable of yielding within certain limits in case of excessive load, the extent of the compression of the spring 18 being limited by the 70 bolts 29 and nuts 30. Thus, if the support is overloaded by too much material falling thereon the power is elastically transmitted to the said support. But after a certain amount of compression the spring will undergo no further compression, owing to the nuts 30 coming in contact with the adjoining face of the flange on the stud 20, so that from that moment on the connecting rod 4 will be 75 practically rigid with said stud, so as to effect a positive connection between the crank 80 9^a and the support 1. Thus the said support will be given a slight reciprocating motion even in case of a very heavy load. I have found that if the compression of the spring 85 is not limited the operating mechanism will be rotated in case of an excessive load without imparting any movement to the support 1, the spring 18 being compressed the full length of its stroke, and that in such cases 90 it is necessary to remove the excess of material from the support by hand, which requires much time. But by positively connecting the operating mechanism with the support after the spring has been compressed 95 to a predetermined extent, the support will be reciprocated for gradually removing the excess of material, though under normal conditions the operation is elastic by reason of the spring 18 and excessive strain on the 100 operating mechanism is avoided.

Figs. 5 and 6 show the manner of mounting the frame 10, 11 on a base frame supported for example on standards. As will appear from these figures, the casing 10, 11 is mounted in such a manner that it can not touch the bottom of the gallery in case of deformation of the base frame, which would expose the casing 10, 11 to excessive strain. The base frame comprises a pair of 105 channel irons 32 connected at their ends by channel irons 33 (Fig. 7) by means of two bolts 34 permitting a certain play of the casing 10 relatively to the channel irons 32, and the bottom part of the casing 10 is located 110 at a higher level than the bottom part of the channel irons 32. Thus, in case of deformation of the frame work the channel irons 32 may be pressed on the ground and bent thereby in the manner indicated in Fig. 6. But 115 such bending is not transmitted to the casing 10.

While in describing the invention reference has been made to a particular example 120 embodying the same I wish it to be understood that my invention is not limited to the construction shown in the drawings, and that various changes may be made in the general arrangement of the apparatus and the con- 125 130

struction of its parts without departing from the invention.

I claim:

1. A propulsion conveyer, comprising an elongated conveying support mounted for being reciprocated in longitudinal direction, an operating mechanism comprising a pair of meshing elliptical gear wheels each rotatably supported at one of its foci, means to connect said conveying support with one of said gear wheels at different angular distances from the major axis of the ellipse of such gear wheel, and means to rotate the other one of said gear wheels.

15 2. A propulsion conveyer, comprising a conveying support mounted for being reciprocated in longitudinal direction, an operating mechanism comprising a pair of meshing elliptical gear wheels each rotatably supported at one of its foci, means to connect said conveying support with one of said gear wheels at different angular distances from the major axis of the ellipse of such gear wheel, within a range extending to about 180°, and 25 means to rotate the other one of said gear wheels.

3. A propulsion conveyer, comprising a conveying support mounted for being reciprocated in longitudinal direction, an operating mechanism connected with said conveying support and comprising a pair of meshing elliptical gear wheels, an adjustable disk, a crank pin on such disk, means for connecting such disk with one of said gear wheels 35 to bring the crank pin into different positions relatively to the major axis of such elliptical gear wheel, a connecting rod connecting said crank pin and conveying support, and means to rotate the other one of said 40 gear wheels.

4. A propulsion conveyer, comprising a conveying support, mechanism for imparting reciprocating movement to said support, a frame on which said mechanism is mounted, and a yieldable base frame on which said frame is yieldingly mounted.

5. A conveyer comprising a conveying support arranged for reciprocating motion, a driving mechanism including a pair of meshing elliptical gear wheels, and an operative connection between one of said wheels and said support, the said connection being adjustable as to its point of actuation by such gear wheel, which point may be set at different angular distances from the major axis of the ellipse of such gear wheel.

6. A conveyer comprising a conveying support arranged for reciprocating motion, a driving mechanism including a pair of meshing elliptical gear wheels, and an operative connection between one of said wheels and said support, the said connection including a crank pin secured to said wheel adjustably, to set such pin in any one of a plurality of positions equidistant from the axis

about which said wheel is mounted to rotate.

7. A conveyer comprising a conveying support arranged for reciprocating motion, a driving mechanism including a pair of meshing elliptical gear wheels, and an operative connection between one of said wheels and said support, the said connection including a disk connected with said wheel rigidly, another disk adjacent to the first-mentioned disk, securing members connecting said disks, 75 one of the said disks having portions for the reception of said securing members which portions are disposed in an annular series the center of which is upon the axis of rotation of said wheel, to permit of a circumferential adjustment of said second disk relatively to the first, and a crank pin carried by said second disk and operatively connected with said support.

In testimony whereof I hereunto affix my signature.

ERNST HOFFMANN.
